US00D741211S

(12) **United States Design Patent**
Kahn et al.

(10) **Patent No.:** **US D741,211 S**
(45) **Date of Patent:** **** Oct. 20, 2015**

(54) **WRISTBAND WITH INTEGRAL CONNECTOR**

(71) Applicants: **Philippe Kahn**, Santa Cruz, CA (US);
Arthur Kinsolving, Santa Cruz, CA (US)

(72) Inventors: **Philippe Kahn**, Santa Cruz, CA (US);
Arthur Kinsolving, Santa Cruz, CA (US)

(73) Assignee: **DP Technologies, Inc.**, Scotts Valley, CA (US)

(**) Term: **14 Years**

(21) Appl. No.: **29/440,218**

(22) Filed: **Dec. 19, 2012**

(51) LOC (10) Cl. **11-01**

(52) U.S. Cl.

USPC **D11/3**

(58) **Field of Classification Search**

USPC D11/1-27; 63/1.11, 1.12, 1.13, 1.14, 63/12, 3, 3.1, 3.2, 4, 5.1, 7, 11, 15, 15.3, 63/32, 33, 34, 38, 41; D14/186, 344
